UNITED STATES PATENT OFFICE.

GEORGE BAZUTKA, OF NEW YORK, N. Y.

TOBACCO-PIPE CLEANER.

Application filed September 18, 1924. Serial No. 738,481.

To all whom it may concern:

Be it known that I, GEORGE BAZUTKA, a citizen of the United States, residing at New York, in the county of New York and 5 State of New York, have invented certain new and useful Improvements in Tobacco-Pipe Cleaners, of which the following is a specification.

This invention relates to a tobacco pipe cleaner and has for its prime object to provide a device of this nature which is efficient in removing the incrustation of carbon and like material which forms on the interior of a tobacco pipe.

Another important object of the invention is to provide a device of this nature which is simple in construction, easy to manipulate, readily carried about, reliable, inexpensive to manufacture, and well adapted to 20 the purpose for which it is designed.

With the above and numerous other objects in view as will appear as the description proceeds, the invention resides in certain novel features of construction, and in 25 the combination and arrangement of parts as will be hereinafter more fully described and claimed.

In the drawing:

Figure 1 is a view showing a pipe with 30 the bowl in section and my device applied thereto,

Figure 2 is a transverse section therethrough substantially on the line 2—2 of Figure 1 looking downwardly,

Figure 3 is another section therethrough taken substantially on the line 3—3 of Figure 1,

Figure 4 is a plan view of the open end of a tobacco pipe bowl showing my invention 40 applied thereto,

Figure 5 is an elevation of a modified form of the invention,

Figure 6 is a longitudinal section therethrough substantially on the line 6—6 of 45 Figure 5,

Figure 7 is a detail perspective of an attachment for this modification,

Figure 8 is a perspective view of a second modification of the device, and

Figure 9 is a perspective view of the 50 sheath for the device.

Referring to the drawing in detail and the form of the invention shown in Figures 1 to 4 inclusive it will be seen that 1 designates the body or blade of the device which

is constructed at one end with the curved edge 2 which is adapted to be engaged with the bottom of the tobacco pipe bowl as indicated in Figure 1. The two side edges 3 of the blade are substantially straight and form the terminals of the beveled portions 4. A cross head 5 is formed integral with the end of the blade 1 opposite to that which is curved and is substantially wider than the blade so as to form shoulders 6 upon 60 which are mounted scraping elements 7 which are adapted to clean the open end of the pipe bowl. The modification shown in Figure 8 is identical with that shown in Figures 1 to 4 except that the scraping elements 7' are inclined for scraping the open end of the bowl when the same is beveled inwardly. In these two modifications it is to be noted that the device tapers slightly both in width and thickness from the cross head 70 75 to the curved end 2. The sheath 8 shown in Figure 9 is shaped to conform to the configuration of the blade 1 when the device is not being used. This sheath may be made of any suitable material sheet metal being 80 preferable. This sheath protects the pocket in which the device may be carried. It is advisable that the device be carried on a key ring or the like and for this purpose an eye 9 is provided on the upper edge of the head 5. A button or like projection 10 is formed on the sheath in order that it may be easily fitted over the blade or taken therefrom.

In the two modifications of the invention just described the blade is made to fit the bowl and of course must be placed on the market in different sizes. It is placed in the bowl as shown in Figure 1 and then twisted or rotated so as to scrape the incrustation 90 of carbon or other material from the interior of the bowl and the elements 7 will scrape similar incrustation from the open end thereof.

Some pipe bowls are constructed with the 100 lower or inner end thereof having a larger diameter than the open ends. Such a pipe bowl is indicated in dotted lines in Figure 5 and the modification shown in Figures 5, 6 and 7 is adapted to accommodate such a 105 pipe bowl. In this modification the blade 11 is of substantially the same construction as the blade 1 and the cross head 12 is of substantially the same construction as cross head 5. An attachment 13 shown to advan-

stage in Figure 7, however, is associated with the device forming a carriage in which the blade is adapted to rock. This attachment consists of a plate 14 having a longitudinally extending rectangular opening 15 therein and on its side edges being provided with the two apertured ears 16. The blade is extended through the opening 15 and a pin 16 is extended through the apertured ears 16 and an opening provided in the cross head 12 so that the blade may rock in respect to the attachment. This modification of the device is placed in the bowl substantially as shown in Figure 5 and it will be seen that it may be rocked so as to cause its scraping edge to contact with the interior surface of the pipe bowl even though the diameter of the bowl should be larger at its closed end than at its open end. The attachment acts as a scraping element for the open end. It will thus be seen with this device the incrustation of carbon and similar material may easily be removed by such a pipe.

It is thought that the construction and operation of the invention should now be clearly understood without a more detail description thereof. While the preferred embodiments of the invention have been described in detail, it will be understood that I do not wish to be limited to the particular construction set forth, since various changes in the form, material, proportions, and arrangement of parts, and in the details of construction may be resorted to without departing from the spirit and scope of the

invention as hereinafter claimed or sacrificing any of its advantages.

Having thus described my invention, what I claim as new is:

1. A pipe cleaning device of the class described including a blade, an attachment for the blade rockably mounted thereon including a plate having an elongated opening therein through which the blade extends, said attachment acting as a scraping element for the open end of a pipe bowl while the blade acts as a scraping element for the interior thereof.

2. A pipe cleaning device of the class described including a blade, a head formed on one end of the blade, an attachment associated with the blade formed from an elongated plate having a slot thereof through which the blade extends, and means for pivotally engaging the plate with the head.

3. A tobacco pipe cleaning device of the class described including a blade, a head formed on one end of the blade, an attachment including an elongated plate having a slot formed longitudinally therein and a pair of apertured ears formed on its side edges, said blade extending through the slot of the plate, and a pin extending through the apertured ears and the head to pivotally mount the attachment thereon.

In testimony whereof I affix my signature in the presence of two witnesses.

GEORGE BAZUTKA.
